Des. 233,853
Patented Dec. 3, 1974

233,853

TUMBLER FOR GEM STONES

Joseph A. Ferrara, 2809 Industrial Parkway,
Santa Maria, Calif. 93454

Filed Sept. 5, 1972, Ser. No. 286,829

Term of patent 14 years

Int. Cl. D15—09

U.S. Cl. D55—1 D

Fig. 1

Fig. 3

Fig. 4

Fig. 5

FIG. 1 is a top view of a tumbler for gem stones, showing my new design;

FIG. 2 is a side view thereof;

FIG. 3 is an end view thereof as seen from the left in FIG. 2;

FIG. 4 is an end view thereof as seen from the right in FIG. 2; and

FIG. 5 is a bottom view thereof.

I claim:

The ornamental design for a tumbler for gem stones, substantially as shown.
